[57] CLAIM

The ornamental design for the smokeless tobacco can
holder, as shown and described.

DESCRIPTION

FIG. 1 is a perspective view of a first embodiment of the
smokeless tobacco can holder showing our new design;

FIG. 2 is a front elevational view thereof;

FIG. 3 is a top plan view thereof;

FIG. 4 is a bottom plan view thereof;

FIG. 5 is a rear elevational view showing a tape attachment;

FIG. 6 is a rear elevational view of a second embodiment
showing a clip attachment, the front being the same as FIG.

1;

FIG. 7 is a side elevational view of a first embodiment, with
the opposite side being a mirror image thereof; and,

FIG. 8 is a side elevational view of a second embodiment,
with the opposite side being a mirror image thereof.
